ATTACHMENT FOR PORCH SWINGS

Filed July 2, 1928

UNITED STATES PATENT OFFICE

WILLIAM H. FRY, OF KANSAS CITY, MISSOURI

ATTACHMENT FOR PORCH SWINGS

Application filed July 2, 1928. Serial No. 289,876.

This invention relates to porch swings and especially to that type which is suspended and provided with a swing propulsion foot rest.

5 The principal object of the present invention is the provision of a porch swing having a seat member carried by a front and rear pair of flexible suspending members and having a swing propulsion foot rest pivotally carried by said seat member and adapted to 10 flex a pair of said suspending members as the same is oscillated.

A further object of this invention is the contemplation of a porch swing having a 15 swing propulsion foot rest provided with means for vertical and longitudinal adjustment.

A still further object of the present invention is an attachment for a porch swing having 20 a pivotally supported swing propulsion foot rest which when oscillated changes the center of gravity of said swing, thereby causing the swing to oscillate.

Other objects are ease of operation, ease of 25 adjustment, and durability of construction.

With these general objects in view as well as minor objects which will appear during the course of the detailed specification reference will now be made to the accompanying 30 drawing in which:

Figure 1, is a perspective view of a porch swing, with some parts partially broken away, embodying this invention.

Fig. 2, is an enlarged fragmentary section 35 taken on line II-II of Fig. 1.

Fig. 3, is an enlarged end elevation of a portion of the foot rest.

Fig. 4, is an enlarged fragmentary view 40 showing the slip joint connection between the foot rest and the flexible suspension member.

Similar reference characters designate like parts throughout the several views and numeral 5 designates a seat member having end members 6, and a pair of front and rear flexible suspending members 7 and 8 respectively.

45 These suspending members are preferably made of chains secured at one end to seat member by means of screw eyes 9 and having at their opposite ends, screw eyes 32 or hooks 50 for attachment to the ceiling. These sup-

porting members are preferably substantially parallel for purposes hereinafter set forth. The front pair of suspending members 7, are provided with elongated links 10 which are preferably positioned in said chains adjacent 55 their lower ends.

Rigidly attached to each of end members 6, by means of screws 11, is a forwardly extending bracket 12 having its outer extremity vertically bifurcated.

60 The swing propulsion foot rest 13 is provided with vertical arms 14 pivotally mounted in brackets 12 by means of pivots 15. Intermediate the ends of arms 14 and below pivot 15 is a sleeve section 16 by means of 65 which said arm may be lengthened or shortened at will and secured in a predetermined position by set screw 17 which is screw threaded in said sleeve section. The upper end of arm 14 adjacent the bracket 12 is provided with a series of transverse holes 18 for receiving the pivots 15 to support said arm in different vertical positions. As clearly 70 shown in Fig. 1, the upper portion of arm 14 extends above the pivotal point 15 and is provided with a rearwardly extending arm 22 having a vertical opening 19 for the reception of the elongated link 10 and through which the link is free to move as the swing propulsion foot rest is operated.

75 To prevent undue wear of arm 22 and link 10 I have provided a suitable bushing 20 which fits in the opening 19 and around the link 10. Also to prevent accidental pinching of the hands of occupants of the swing a flexible shield 21 which is adapted to cover the outer end of arm 22 and a portion of the elongated link 10 is provided. The lower portions 23 of arms 14 are oppositely disposed and adapted to slidingly engage the 80 connecting sleeve 24 for longitudinal adjustment. When the members 23 and 24 are properly adjusted as to length the set screws 25 carried by sleeve 24 are securely set against members 23 to hold the parts in a fixed relative position.

Extending forwardly and substantially at right angles to arms 14 are supporting arms 26 and 27 respectively. Horizontally extending bars 28 are securely attached to support 100

ing arm 26 at one end by means of rivets 29, while the opposite ends of said bars are slidably mounted in loops 30 formed on the upper side of supporting arm 27. With the construction as described and shown it is apparent that the foot rest may be adjusted to swings of different lengths, and when so adjusted, if the bars 28 extend too far through loop 30 a portion of the same may be cut away.

10 In the operation of this swing the seat member with the foot rest properly adjusted is suspended as described above so that it is free to swing. The operator when positioned 15 in the swing with his feet resting on the bars 28 may oscillate the swing by pressing forwardly or rearwardly on the bars, thereby causing the foot rest to oscillate about pivots 15. This oscillation in turn causes the flexing 20 of the front pair of suspending members. This flexing of the suspending members and the resultant changing of the relative positions of the seat member and foot rest will disturb the equilibrium of the swing and 25 cause it to oscillate to a degree commensurate to the force applied to the foot rest. Likewise, when the swing is in motion it may be brought to rest by simply applying foot force to the foot rest in counter direction to 30 the movement of the swing.

While the foot rest has been shown and described as flexing the front pair of suspending members, yet it is apparent that the operation would be substantially the same if 35 the rear pair of suspension members was flexed.

I do not limit this invention to the construction shown and described, as many modifications may be made within the scope of the 40 appended claim without departing from the spirit thereof.

What I claim is:

A porch swing comprising a seat member, a front and rear pair of suspension members 45 for said seat member, a swing propulsion foot rest pivotally carried by said seat member and having a pair of arms extending above the pivot points and engaging the front pair of suspension members and adapted to flex 50 one pair of suspension members forwardly and rearwardly as said foot rest is moved to and fro relative to said seat member, said arms being adjustable to vary the relative movement between said flexible suspension 55 members and foot rest.

In testimony whereof, I hereunto affix my signature.

WILLIAM H. FRY.
